UNITED STATES PATENT OFFICE.

WILLIAM S. HADAWAY, JR., OF NEW YORK, N. Y.

ELECTRIC HEATING DEVICE.

1,098,437.

Specification of Letters Patent. Patented June 2, 1914.

Application filed September 13, 1911. Serial No. 649,124.

To all whom it may concern:

Be it known that I, WILLIAM S. HADAWAY, Jr., a citizen of the United States, residing at New York, in the county of New York and State of New York, have invented new and useful Improvements in Electric Heating Devices, of which the following is a full, clear, concise, and exact description, reference being had to the accompanying drawing, forming a part of this specification.

My invention relates to electric heating devices.

It has among its objects to provide an improved electric heating device wherein the heating unit is inclosed in a protecting casing and the parts of the heater may be readily assembled or disassembled when desired.

A further object of my invention is to provide an electrical heating device which is particularly adapted to service as a soldering iron, wherein an efficient heating unit is inclosed in a protecting casing which serves to protect the same from the action of the fluxes and the device may be readily assembled or disassembled.

Other objects and advantages of my improved construction will hereinafter appear.

In the accompanying drawings I have shown one form which my invention may assume in practice. My invention is not, however, limited to this specific form chosen for purposes of illustration.

In the views of these drawings:—Figure 1 shows a side elevation of the heater with a portion of the casing broken away. Fig. 2 shows a longitudinal sectional view of the same. Fig. 3 shows a detail view of the head of the iron. Fig. 4 shows a plan view of the heating element and its connecting lead. Fig. 5 shows a sectional view on line 5—5 of Fig. 4. Fig. 6 shows a detail view of the connection of the lead to the unit. Fig. 7 shows a sectional view of the lead.

In the construction shown in the drawing I have illustrated a heating unit 1, herein-after described, inclosed in an outer shell 2, having a projecting tubular portion 3 of reduced diameter. The tip 4 of a soldering iron having a shank 5 of reduced diameter, is inclosed within the heating unit and held in position by clamping rings 6 which are slipped over the casing 2 to compress the same upon the unit. The terminals of the heating unit 1 are led out through leads 7 inclosed within the portion 3 of the casing 2

to suitable binding posts 8, within a handle 9 carried upon the end of the tubular member 3.

The heating unit is shown in Figs. 1, 2, 4, 5, and 6. As illustrated in these figures, it comprises a resistance material 10 which is inclosed between sheets of insulation 11 and incased between sheets of soft metal 12. In a preferred form (Figs. 4, 5 and 6) I use a reflexed resistance wire, formed of a high resistance alloy such as nickel chromium or copper nickel as the resistance material, wind the same flatwise on an insulating base and then inclose this resistance material between two sheets of mica. However, other materials may be used if desired. The two metallic sheets 12 which inclose the sheets of insulation may be formed of any suitable metal having a sufficiently high melting point to withstand the heat of the unit and which, when compressed, is soft enough to receive the harder reflexed resistance material so that the parts of the unit form a single compact unitary structure. For example I may use either copper or aluminum as the materials for these plates. When the unit is assembled with the resistance material inclosed between the sheets of insulation the two metal sheets 12 are compressed around the unit, preferably before the parts are rolled, and the edges of the metallic plates are brazed so that the resistance material is hermetically sealed within the unit.

As illustrated in Fig. 4, the leads for the heating unit are formed of a plurality of fine wires, and these fine wires are interwoven with the reflexed material. In a preferred form the leads are insulated as for instance with asbestos as shown at 13, Fig. 7, and are preferably inclosed in a tubular member 14, preferably elliptical in cross section as shown in Fig. 7. In a preferred form this tubular member 14 is of a sufficient length to extend from the heating unit out through the tubular member 3 to the end of the handle 9, so that the conductors may be brought directly out to the binding posts. In a preferred form the inner end of the tubular member 14 is flattened out to form plates 15 shown in Fig. 6, which are compressed upon the corner of the unit, as shown in Figs. 4 and 6, and then brazed to the metallic inclosing casing of the unit. Thus a very tight and rugged connection is made with the unit so that there is no dan-

ger of the parts being separated in service or in assembling and it is impossible for the fluxes to enter the unit.

- When it is desired to assemble the iron 5 the heating unit shown in Fig. 4 is bent into cylindrical form so that it will inclose the shank 5 of the tip, as shown in Figs. 1 and 2. As illustrated in these figures, the unit fits tightly around the shank 5. In a preferred 10 form this is accomplished by making the outer casing 2 of a split form and providing means for forcing the parts together to compress the unit upon the tip, and the casing upon the unit. In a preferred form the 15 outer casing is made up in two parts which are suitably secured together at one end by engaging lugs 16, and the outer walls of the outer casing 2 are tapered so that the clamping rings 6 may be forced over the same to compress the casing and bring the edges of the slit 17 together. In order to position the unit and the tip within the casing, struck-in portions 18 are preferably provided on the outer casing 2. These portions 20 25 serve as stops for the tip, and in order to receive the same and provide a snug fit the tip is preferably provided with cut-away portions 19. In a preferred form the struck-in portions 18 are located opposite each 30 other on the opposite halves of the outer casing. In addition to the struck-in portions 18 a struck-in portion 20 is also provided, one half of the same being preferably on each half of the outer casing. This 35 struck-in portion is housed in a suitable cut-away portion 21 in the inner end of the tip, as shown in Fig. 3. Thus the tip and heating unit are firmly clamped together and held in position while they may at the same 40 time be readily removed, if desired.
- It is of course obvious that the handle 45 may be secured to the tubular member 3 in any desired manner, as for instance by screws 22. In a preferred form the handle is provided with a removable tip 23 attached to the body of the handle by suitable screws 24, and this tip is provided with a central opening 25, through which the leads may be brought to the binding posts 8.
- By my improved construction I have 50 provided a soldering iron wherein the tip may be readily and quickly removed by simply loosening the clamping rings. Further, I have provided a soldering iron 55 wherein the heating unit is inclosed in a metallic casing so that the heat is directly conducted to the tip. Further, the heating unit and the leads are so protected by the casing that it is impossible for the fluxes used in 60 the soldering process to gain access to the inside of the same and thus destroy the unit. Further, the heating unit is inclosed in an outer casing which accurately positions both the unit and the tip and which may be 65 readily removed when desired. Further, the

heating unit in my improved construction is arranged as near the exterior as possible, so as to permit the surplus heat to be radiated from the inclosing outer casing. Further, by the provision of the stiff stem containing the leads for the heating unit, I have been able to greatly facilitate the connections of the terminals to the device and protect both the unit and the leads from the action of the fluxes used. By the use of the soft metal casing for the unit, I have also been able to provide a casing which not only directly conducts the heat to the tip, but also serves as a gasket between the parts, so that the union is a very intimate one.

80

While I have in this application described one specific form which my invention may assume in practice, I do not wish to be limited to this specific form chosen for purposes of illustration, but wish rather to include all of those forms which fall within the spirit of my invention.

85

What I claim as new and desire to secure by Letters Patent is:

1. In an electric soldering iron, a soldering tip having a shank, a heating unit therefor inclosed and sealed in a metallic casing, and means for compressing said casing into intimate heat conducting relation with the shank of said tip.

90

2. In an electric soldering iron, a soldering tip having a shank, a heating unit therefor inclosed and sealed in a metallic casing surrounding said shank, and removable means inclosing said casing and holding the same in intimate heat conducting relation with said tip.

95

3. In an electric soldering iron, a soldering tip having a shank of reduced diameter, a metallic casing surrounding said shank, a heating unit sealed in said casing, an outer metallic casing inclosing said first mentioned casing, and removable means for clamping the parts together.

100

4. In an electric soldering iron, a soldering tip having a shank of reduced diameter, a metallic casing surrounding said shank, a heating unit sealed in said casing, an outer metallic casing inclosing said first mentioned casing, and a sliding ring movable upon said outer casing for clamping the parts together.

110

5. In an electric soldering iron, a soldering tip having a shank of reduced diameter, a metallic casing surrounding said shank, a heating unit sealed in said casing, a longitudinally divided two-part casing inclosing said first mentioned casing, and removable means for clamping the parts of said casing upon said first mentioned casing.

115

6. In an electric soldering iron, a soldering tip, a metallic casing surrounding a portion of said tip and in intimate heat conducting relation therewith, a heating unit sealed in said casing, and an outer metallic casing inclosing said first mentioned casing.

120

- and having struck-in portions for positioning said unit and said tip.
7. In an electric soldering iron, a soldering tip, a heating unit therefor, a resilient casing inclosing said unit, and means for clamping said unit and said casing snugly to said soldering tip.
8. In an electric soldering iron, a soldering tip, a heating unit therefor, a longitudinally divided casing inclosing the same, and means movable longitudinally of said casing for clamping the latter upon said tip.
9. In an electric soldering iron, a soldering tip, a heating unit therefor, a resilient casing adapted to receive the same and having a tapered wall, and a sliding ring movable upon said casing for clamping the parts together.
10. In an electric soldering iron, a soldering tip having a notch in one end thereof, a heating unit surrounding said tip, and a casing inclosing said heating unit and having means coöperating with said notch to position said tip and said unit.
11. In an electric soldering iron, a soldering tip having a shank of reduced diameter, a heating unit surrounding said shank, and a longitudinally divided resilient casing inclosing said heating unit, said shank having struck-in portions for positioning said tip and heating member.
12. In an electric soldering iron, a soldering tip having a shank of reduced diameter, a heating unit surrounding said tip, and a resilient two-part casing having its parts insulated from each other inclosing said tip and unit.
13. In an electric soldering iron, a soldering tip, a heating unit therefor inclosed and sealed in a metallic casing, a second metallic casing integrally united with said unit casing and acting as a conduit for the leads of said unit, and an outer metallic casing inclosing said first and second mentioned casings.
14. In an electric soldering iron, a soldering tip, a heating unit therefor inclosed and sealed in a metallic casing, a second metallic casing integrally united with said unit casing and acting as a conduit for the unit leads, an outer metallic casing inclosing said first and second mentioned casings, means for clamping said heating unit and said tip within one end of said outer casing, and a handle carried upon the opposite end of said casing provided with terminal connections for said heating units.

In witness whereof, I have hereunto subscribed my name in the presence of two witnesses.
